EDWARD W. ROBERTS,
By Oscar A. Michel Atty.

UNITED STATES PATENT OFFICE

EDWARD WILLIAM ROBERTS, OF CHICAGO, ILLINOIS, ASSIGNOR TO LAKWOOD MANUFACTURING CO., OF CHICAGO, ILLINOIS, A CORPORATION OF ILLINOIS

CONTAINER

Application filed September 10, 1930. Serial No. 480,933.

This invention relates to improvements in an insect exterminator commonly known as and called fly killer, its object to provide a receptacle in which is placed a certain quantity of insecticide and by adding a quantity of water thereto, the insecticide becoming dissolved creating a poisonous liquid which is absorbed by an absorbent pad and against which the fly or insect is to contact.

10 A further object of my invention is to provide a receptacle or container of two sections, each arranged to be interlocked together, or in other words firmly secured together by frictional contact, in the receptacle 15 is placed a certain quantity of poisonous powder, and in the upper portion of the receptacle is located an absorbent pad which is to absorb a certain quantity of the poisonous ingredients after water has been inserted to 20 intermingle with the powder and dissolve the same producing a poisonous liquid which when the fly or insect partakes of the same it means extermination.

The device is simple, it is ornamental, and 25 is only operative when liquid is added and the pad soaked with the poisonous liquid.

Figure 1 is a perspective view of my complete invention.

Figure 2 is a top plan view of the same.

30 Figure 3 is a central vertical sectional view.

Figure 4 is a central vertical sectional view of a modified form of my invention.

Figure 5 is a vertical sectional view of the 35 insert used in my modification.

In the general construction of my invention I provide a receptacle comprising a base or bowl member 6 and a cap or cover member 7, the upper portion of the bowl member 40 terminating into a tapered flange 8 and the bottom of the cover member terminating into a tapered flange 9 each being so arranged that when brought together and pressure applied the same will become locked together 45 by frictional contact.

The upper surface of the cover member 7 is cut out in a manner as shown and indicated by the numeral 10 and in the cover and beneath the cut out portion is positioned a pad 50 of absorbent material such as felt or the like

11 and on the top of the pad and beneath the upper surface of the cover is placed a thin layer of colored felt which gives the article a neat and finished appearance this layer being indicated by the numeral 12.

55 In the bowl member is located an insert member 13 consisting of a side wall 14 and a top portion 15 its bottom being open, in the top 15 is formed an opening 16 through which is inserted a felt core 17 it likewise passes through a center opening 18 formed in the pad 11, this core is permitted to extend downwardly into the bowl 6 contacting with the liquid acting as a wick which will continuously supply the pad with the poisonous 60 liquid. Around the bottom end of the core is fitted a strip of fabric 19 which extends upwardly through the opening 17 and resting between the top 15 and the bottom of the pad, see Figure 3. This strip prevents the 65 insecticide being removed from the bowl should the core be removed.

The insecticide when in powder form is indicated by the numeral 20 and shown by stipple in Figure 3.

70 The article when assembled for the market is in no wise functional until water is applied, when the article is purchased it contains a certain quantity of powder in the bowl, in order to make it effective, the core 75 is removed and a quantity of water is poured into the container, the core is then placed back in position and the article is shaken and inverted so that the poisonous chemical 80 contacts with the pad and soaks the same 85 then the receptacle can be placed at a convenient location and it is now ready. When a fly sips at the felt, it is the destruction of the fly, thus this article is functional so long 90 as the pad is saturated with the liquid.

95 In Figures 4 and 5, I show a modified form of structure, in this instance the locking or connecting feature by which the two members are secured together consists of a bead formation 21, and the insert member is provided with a central sleeve 22 and of larger diameter than the core 17, by this arrangement and by handling the article before water is inserted the powder in the bowl will nat- 100

urally pass toward the edge of the bowl when tilting the device, and should the article become inverted, it will fall into the cup formation of the insert thereby preventing it from 5 contacting with the felt pad above.

The device is simple and exceedingly effective in the purpose for which it has been intended.

What I claim is:

- 10 1. An article for the purpose set forth comprising two members adapted to have interconnection with respect to each other to provide an enclosed receptacle and one of the members being provided with an opening, a partition member having an opening formed therein in registration with the first mentioned opening and arranged in said receptacle to divide the receptacle into an upper and lower compartment, an absorbent member arranged in the upper compartment and supported by the partition member and having a portion thereof exposed through the first mentioned opening, and a wick member 25 in contact with the absorbent member with one end projecting through the first mentioned opening and having its opposite end portion extending into the lower compartment.
- 30 2. An article for the purpose set forth comprising two members adapted to have interconnection with respect to each other to provide an enclosed receptacle and one of the members being provided with an opening, a partition member having an opening formed therein in registration with the first mentioned opening and arranged in said receptacle to divide the receptacle into an upper and lower compartment, an absorbent member arranged in the upper compartment and supported by the partition member and having a portion thereof exposed through the first mentioned opening, and a wick member 35 in contact with the absorbent member with one end projecting through the first mentioned opening and having its opposite end portion extending into the lower compartment, the end of said wick exposed through the first mentioned opening being of a diameter less than the diameter of the said first mentioned opening and being in contact with the exposed portion of said absorbent member.

In testimony whereof I hereunto affix my signature.

EDWARD WILLIAM ROBERTS.
